BILLET HEATING FURNACE

Frederic O. Hess, Philadelphia, Pa., assignor to Selas Corporation of America, Philadelphia, Pa., a corporation of Pennsylvania

Application August 20, 1952, Serial No. 305,458

5 Claims. (Cl. 263—6)

The present invention relates to furnaces, and more particularly to furnaces through which metal bodies such as ingots and billets are moved one after another to be heated.

It is an object of the present invention to provide a furnace in which the objects to be heated are carried therethrough on an overhead conveyor. It is a further object of the invention to provide a furnace having a plurality of openings or doors in the bottom through which the objects being heated can be removed if they drop from the conveyor.

The invention includes a furnace having a chamber that is directly fired by a plurality of burners. The roof of the chamber has a slot extending lengthwise thereof through which conveying mechanism extends to support the work so that it may be heated evenly on all sides. From time to time the work pieces may drop from the conveyor and obstruct the furnace chamber. The floor of the chamber is therefore provided with or made of a plurality of doors that can be opened individually so that the work pieces thereon may easily be removed.

The various features of novelty which characterize my invention are pointed out with particularity in the claims annexed to and forming a part of this specification. For a better understanding of the invention, however, its advantages and specific objects attained with its use, reference should be had to the accompanying drawings and descriptive matter in which I have illustrated and described a preferred embodiment of the invention.

In the drawings:

Figure 1 is a section view taken through the furnace on line 1—1 of Figure 2; and

Figure 2 is a transverse section of the furnace.

Referring to the drawings, there are shown a pair of foundation beams 1 extending longitudinally of the furnace. Attached to these beams at spaced points are vertically extending supports 2 upon which structure forming a furnace chamber 3 is mounted. This chamber is built in accordance with ordinary furnace practice and includes a metal backing sheet 4 around the sides and top thereof. This backing serves to support a furnace lining of suitable refractory material 5 of a thickness and composition to withstand the temperature of the furnace. The top of the furnace structure is hung from the supports 2 by means of braces 6 welded thereto which extend inwardly from each side thereof. The furnace can be heated by any suitable burners but is preferably heated by burners of the type which produce radiant heat such as those disclosed in Furczyk Patent 2,561,793, issued on July 24, 1951. These burners each include a ceramic block 7 which is embedded in and forms part of the furnace wall. Each block is provided on its face in the furnace chamber with a cup-shaped depression 8 into the base of which extends a distributor 9. Air and gas under suitable pressure are supplied through the distributor from which it is discharged in a plurality of radially directed jets that burn along the surface of the cup 8 to heat the same to incandescence. Radiant heat from

2

the cup, as well as hot products of combustion, heat the walls of the furnace chamber to incandescence and transfer heat to the work. Each of these burners is supplied individually through a pipe 11 and the burners in each row may be connected to a manifold 12. The supply of fuel to each burner can be adjusted individually by a valve 13. As shown herein, the burners are staggered on opposite sides of the furnace chamber, so that the work is heated evenly throughout its entire area as it is being moved longitudinally through the chamber. If desired, suitable automatic controls can be provided to regulate the furnace temperature.

The top of the chamber is provided with a centrally extending slot 14 along the upper edges of which are located water cooled passages 15. These passages are supplied with cooling water at one end by pipes 16, and the cooling water is removed at the opposite end of the furnace.

The bottom or floor of the furnace comprises a plurality of doors which can be opened to give access to the furnace chamber. Each of these doors includes a metal frame in form of a casting 17 that is filled with a suitable refractory material 18, and which extends from the lower edge of one side wall to the lower edge of the other. The frame 17 is pivoted at 19 on a pivot that is parallel to the side walls, so that the doors can be tilted from their full line to their dotted line positions in Figure 1 and thereby permit removal of ingots or billets when such is necessary. Each casting is provided with an arm 21 extending to the right, as shown in Figure 1 of the drawing, and to which is attached a counterweight 22 that is heavy enough normally to hold the door in closed position. This counterweight may be supplemented with a spring if desired. In some cases it may be desirable to lock the doors in their closed position. This is accomplished by a latch plate 23 extending from the left side of casting 17, which plate is engaged by a latch 24 that is pivoted on the right side of the furnace frame at 25. Some suitable gasket material such as asbestos rope will be placed around the edge of each door to make a tight seal between the door and the furnace side walls to thereby prevent infiltration of air into the furnace chamber.

Work in the form of billets or small ingots 26 is carried through the furnace by means of a conveying mechanism which travels along the top of the furnace. This mechanism includes a rod 27 that extends through the slot 14, and which has a hook on its lower end that engages a ring or stud 28 welded to the top of the billet. The upper end of the rod is fastened to a carrier 29 that is provided with rollers 31 which engage the flanges of a track 32. This track extends lengthwise of the furnace and is supported by crosspieces 33 which are attached to the upper ends of the vertical supports 2. Each 55 of the billet carriers is provided with a heat seal to prevent loss of heat through the roof of the furnace which includes a shield 34 through which the rod 27 extends. The rod is provided with a collar 35 in order to keep the shield 34 from falling below a predetermined point 60 when the carriers are out of the furnace. Skid plates 36 extend along the upper surface of the channels 15 for the shield to ride along as the carrier is moving a billet through the furnace.

The ends of the furnace chamber are closed by doors 65 similar to the one shown at 37 in Figure 2. The door is guided for vertical movement and is opened by lowering it below the floor level. The door is raised and lowered by counterweighted cables 38 that pass over pulleys 39 attached to the furnace supported structure.

Prior to the time the billets 26 are heated, a ring 28 or some similar supporting device is fastened to the top thereof as by welding. The billets are then placed on

the hooks of the carriers 27 and are ready to be heated. Periodically, the door 37 is opened and a carrier is rolled along the track to move a billet into the furnace. As the billets progress through the furnace, they are heated to a forging or extrusion temperature in the neighborhood of 2250° F. This heat is produced by the burners predominately in the form of radiant heat, but also by hot products of combustion. Ordinarily, the cups of the burners of this type are heated to a temperature in the neighborhood of 2800° F., and the furnace chamber itself will be a few hundred degrees lower or in the neighborhood of 2500° F. With a temperature gradient of this type, a billet of alloy steel 6.35 inches in diameter and 28 inches long weighing 250 pounds can be brought up to a forging temperature in 24 minutes or less. The radiant heat produced by the furnace will heat the billets evenly throughout their volume, so that by the time they are removed from the other end of the furnace, they can be placed directly in a forging or extrusion press. The fuel-air ratio supplied to the burners is controlled so that there is normally a neutral atmosphere of products of combustion in the furnace chamber, and thus there is practically no scale formed on the billets during the heating process.

From time to time defective welds will be formed between the supporting members 28 and the billets 26. A billet having one of these defective welds will frequently fall from the conveyor, and will block the passage through the furnace chamber if provision is not made for removing these billets. Since the bottom of the furnace consists of a plurality of doors that are counterbalanced to a closed position they will open individually when a billet falls on them. The billet is thereby quickly removed from the furnace without losing a great amount of heat from the chamber and without interrupting the heating process of the remaining billets. If the latches 24 are being used, it is only necessary for the operator to release the latch of the door upon which the fallen billet is resting in order for it to be removed.

From the above, it will be seen that I have provided a furnace through which billets are conveyed by an overhead structure one after the other as they are being heated. The furnace floor consists of a plurality of doors through which individual billets can be removed, if for some reason they should fall from the conveying mechanism. The billets can be moved directly through the furnace on a production line basis to a point upon which work is performed on them.

While in accordance with the provisions of the statutes, I have illustrated and described the best form of embodiment of my invention now known to me it will be apparent to those skilled in the art that changes may be made in the form of the apparatus disclosed without departing from the spirit and scope of the invention as set forth in the appended claims, and that in some cases certain features of my invention may be used to advantage without a corresponding use of other features.

What is claimed is:

1. In a furnace system, the combination of structure forming an elongated furnace chamber having side walls, a roof and a floor said roof being provided with a slot extending lengthwise thereof and through which is adapted to extend a conveyor to carry billets to be heated in

said chamber, said floor being formed of a plurality of sections extending between the lower edges of each side wall, means to mount each section for movement between a first position in which it closes the space between said side walls and a second position in which said space is open, and means to bias said sections normally to their first position, said floor sections moving to their second position against the action of the biasing means to discharge billets dropped by the conveyor.

2. In a furnace system, the combination of structure forming an elongated chamber having side walls and a roof, said roof being provided with a slot extending centrally thereof from one end to the other, a plurality of burners located in said side walls to supply heat to said chamber, a floor for said chamber being formed of a plurality of doors extending between the lower edges of said side walls, means to mount said doors for pivotal movement around an axis below and parallel to one of said side walls, and latch means operative to hold said doors in closed position extending between said side walls.

3. A furnace comprising vertical supports, structure mounted on said supports forming an elevated furnace chamber substantially rectangular in section, said structure forming side walls, burners for heating said chamber mounted in said side walls, said structure also including means forming a roof for said chamber with the roof having a slot running lengthwise thereof from end to end through which a conveying mechanism for carrying work to be heated is adapted to extend, and said structure including means forming a bottom for said chamber consisting of a plurality of sections, pivot means to support each of said sections for swinging movement parallel to one of said sides whereby when work is dropped from the conveying mechanism it can be removed from the chamber through one of said sections, and means to bias each section normally to its closed position against the lower edges of said sides.

4. The combination of claim 3 including means to latch positively each of said sections in its closed position.

5. Apparatus for heating billets comprising structure forming the side walls and roof of an elongated furnace chamber, said roof being provided with a slot extending from one end to the other thereof, a plurality of doors forming the floor of said chamber, each door engaging the lower edge of each of said sides, means to mount each door below one of said sides and for pivotal movement around an axis parallel to said side, means to maintain each of said doors in its normal closed position, and a door at each end of said chamber through which work to be heated can be moved as it is carried by mechanism that is adapted to extend through said slot.
